CLAIM

The ornamental design for a chair, as shown and described.

DESCRIPTION

FIG. 1 is a perspective view of a chair showing my new design;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a bottom plan view; and,

FIG. 7 is a cross-sectional view taken along line 7—7 of FIG. 4.

The broken lines shown under the chair in FIG. 1 represent ground and form no part of the claimed design.

FIGS. 2 through 6 have been shown on an enlarged scale and FIG. 7 has been shown still further enlarged with respect to FIG. 1.
